AQUATIC DEVICE

Application filed January 6, 1932. Serial No. 585,000.

This invention relates to improvements in aquatic devices and more particularly to a hand controlled device for facilitating swimming.

5 It is one of the objects of this invention to provide a self-sustained swimming device which is provided with a retractible paddle so that a swimmer may force the device through the water with substantially little 10 resistance in one direction, and may use it as a control in the return direction.

Another object of this invention is to provide a portable hand operated swimming float with a self opening retractible paddle

15 for assisting the swimmer and which will be self sustaining to prevent not only its own loss in the water, but which will assist in sustaining a person otherwise sinking and unable to float.

20 Another object of this invention is to provide a hand operated float having a water catching self opening, scoop for swimming and so arranged that the operator may swim faster and more safely than with heretofore known swimming aids.

Another object of this invention is to provide a swimming aid for swimmers and those learning to swim which will teach them the overarm stroke and assist not only in propulsion through the water but will also prevent drownings.

Further objects and advantages of this invention will appear from the following description thereof taken in connection with the attached drawing which illustrates a preferred form of embodiment thereof and in which;

Figure 1 is a side elevation of the aquatic device,

40 Figure 2 is an end elevation of the device shown in Figure 1 with the paddle in dotted line to show it on the return stroke,

Figure 3 is an enlarged detail partly broken away and taken substantially on the line 3—3 to show the paddle securing construction.

Previous devices for promoting swimming, particularly among children, such as water wings, inflated rubber tubes and the like often 50 result in a false sense of security in which

the child will paddle out beyond his depth and may slip through the inflated tube or away from the water wings with the result that the child may find himself in danger of drowning. One of the advantages of our 55 invention is that it does not provide a false sense of security and in use the child or adult will naturally accustom himself to movement of the device with a swimming motion so that the use of the device automatically teaches a 60 form of swimming stroke and does not encourage the child to go beyond his depth before acquiring proficiency in the use of our swimming device.

The swimming device shown, which is illustrative of one preferred form of construction consists of a float 10 which may be hermetically sealed, and although preferably made of sheet metal, may be made of cork, balsa wood or other material which will float 70 and offer a support for the remaining parts. A hand grip may be made integral with or secured to the float 10 by any suitable means such as straps 14 which are secured by the rivet 16. The straps 14 also carry the 75 retractible paddle or scoop 18 which is secured to the float at a point substantially near the end of the float opposite the hand grip 12. As shown in Figure 2, the paddle 18 is adapted to pivot on the supports 14a by means of 80 the pivot 19 which passes through the projecting ears forming the supports 14a on the straps 14. This construction is more clearly shown in Figure 3 and has been found suitable. 85

The paddle or scoop 18 is so arranged that as the paddle is pushed away from the swimmer, the water will engage the bottom side of the paddle 18 and force it into the closed position as shown in the full lines in Figure 2. In such position, the paddle rests against the abutment 20 on the strap 14 which is preferably made by using a strap larger than necessary and bending the ends into substantially L shape to engage the paddle in the closed position. The paddle 18 is however, still at a small angle to the float body 10 and the movement away from the swimmer will cause the float to rise not only due to its own 100

buoyancy but also due to the reaction of the water on the inclined paddle.

When the paddle is drawn toward the swimmer, the water will engage the inner side 5 of the paddle 18 and force it to swing open until the rear part of the paddle 18 engages the strap 14 at the point 14b adjacent the end of the float. In such position the paddle offers a substantial scoop like effect and the 10 operator may exert a very powerful pulling force by such means.

The paddle is preferably made of wood and may be of a size approximately the size of the float. The handle 12 is also preferably 15 made of wood so that the entire swimming device will float and has sufficient buoyancy to effectively aid in preventing a sinking person from submersion. The device, however, also has the advantage that it may be practically 20 used for extremely rapid swimming in that the swimmer can draw the paddle through the water materially increasing his power on the return stroke and not appreciably hindering the passage of the paddle 25 through the water on the forward stroke. The use of wood in the handle and paddle tends to increase the sense of security in the user although it is to be understood that the paddle could be made of any sufficiently thin, 30 light and strong metal such as aluminum and the handle could be made of any similar suitable material. While the tank is preferably sheet metal which may be easily formed and rendered air tight it may also be made of material 35 that will float and which is not relatively heavy such as cork, etc.

It is also to be understood that various other means may be provided for securing the handle and the paddle to the float and that 40 the size and shape may be varied as desired. It is expected that the device will be used in pairs, one for each hand, although such construction is not essential. The abutment for the paddle may also be changed to afford 45 either a greater closing or a lesser closing of the paddle and it may be mounted on the paddle itself or as desired.

The device may be used in various swimming strokes such as the breast stroke in 50 which it is pushed forward and drawn back in an almost straight line or in an overhand stroke in which the arms and the float are thrown forward above the water and drawn back toward the body underneath the water.

55 While we have shown a preferred form of embodiment of our device we are aware that other modifications may be made therein and we therefore desire a broad interpretation of our invention within the scope and spirit of 60 the disclosure thereof and of the claims appended hereinafter.

We claim:

1. An aquatic device comprising a float member and a retractible scoop and means 65 to project said float member through the

water to retract the scoop in one direction and to pull the float through the water in another direction to open said scoop to increase the resistance to movement, said float projecting means including a gripping member, 70 said gripping member and said scoop being secured to opposite ends of said float member.

2. An aquatic device of the class described 75 comprising a self-sustaining float, a buoyant retractible paddle mounted substantially at one end thereof and a buoyant hand grip mounted on the end opposite said retractible paddle, and means to freely pivot said paddle on said float whereby said paddle will open 80 when said float is pulled through the water to cause an increase of resistance to such movement and to allow said paddle to partially close on reverse movement of said float.

3. A swimming help of the class described 85 comprising an air tight tank, a hand grip secured to said tank substantially near the end thereof, and a paddle pivoted on the opposite end of said tank to increase the resistance of movement of said tank in one direction, 90 said paddle partially closing to decrease the resistance to movement of the tank in the other direction by deflecting said tank upwards.

4. A swimming help comprising a portable 95 fluid supported body and scoop pivoted intermediate its ends to said body, said scoop being movable to open position in one direction of movement one part of said scoop forming a pocket with the body and closing 100 in the opposite direction, said scoop being spaced from said body in such position, said body being buoyant and adapted to support a swimmer.

5. A swimming help of the class described 105 comprising a buoyant member, a hand grip secured to said buoyant member, a buoyant paddle, means to pivot said paddle to said buoyant member, said paddle being spaced below said buoyant member in normal position, means to space said paddle from said buoyant member in a closed position so that said tank may be projected through the water with a minimum of resistance in one direction, 115 said paddle adapted to close against said tank in the return direction to materially increase the resistance to movement and to facilitate high speed swimming, the hand grip, buoyant member and scoop pivoting means being in alignment so that any 120 pull on said hand grip will tend to open said paddle to operative position.

6. As an article of manufacture of the class 125 described a body member, a paddle member, and means to hinge said paddle member with respect to said body member substantially near one end of said body member and intermediate the ends of said paddle member, said paddle member adapted in one position to lie at a small angle to but spaced from said 130

body member and in a second position, said paddle member lying at a substantial right angle to said body member and in closed relation with the end thereof.

5 7. As an article of manufacture of the class described, an aquatic device comprising a buoyant member, a foldable scoop secured thereto and a hand grip, means to hold said scoop at a small angle to said buoyant member when said buoyant member is moved away from the operator to raise said buoyant member, and means to hold said scoop at a substantial right angle to said buoyant member when said member is moved in the opposite direction to cause said member to act as a scoop, the hand grip and scoop being on the same side of a water level line through the buoyant member so that a pull on the hand grip will open the scoop to the right angle position.

10 8. As an article of manufacture of the class described, an aquatic device comprising a buoyant member, and a foldable scoop secured thereto, means to hold said scoop at a small angle to said buoyant member when said buoyant member is moved away from the operator to raise said buoyant member, said scoop being pivoted intermediate its ends, said shorter portion contacting with said buoyant member to hold said scoop in a pocket relation to said buoyant member.

15 9. As an article of manufacture of the class described, an aquatic device comprising a buoyant member, and a foldable scoop secured thereto, means to hold said scoop at a small angle to said buoyant member when said buoyant member is moved away from the operator to raise said buoyant member, said scoop being pivoted intermediate its ends, said shorter portion contacting with said buoyant member to hold said scoop in a pocket relation to said buoyant member, and a hand grip mounted on said buoyant member opposite to said scoop.

20 45. In testimony whereof we have affixed our signatures to this specification.

GERTRUDE C. EDERLE,
CADWALLADER W. KELSEY.
